COMBINED TOOTHBRUSH AND TUMBLER HOLDER

Kenneth M. Solberg, 4807 SW. Barton St.,
Seattle, Wash.

Filed May 15, 1964, Ser. No. 80,000

Term of patent 14 years

(Cl. D4—3)

The dominant features of my design reside in the full-line portions of the drawing.

I claim:

The ornamental design for a combined toothbrush and tumbler holder, substantially as shown and described.
